CLAIM

The ornamental design for a display screen with an animated graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a first image of a sequence of a display screen with an animated graphical user interface showing our new design.

FIG. 2 is a second image of a sequence of a display screen with an animated graphical user interface showing our new design.

FIG. 3 is a third image of a sequence of a display screen with an animated graphical user interface showing our new design.

FIG. 4 is a fourth image of a sequence of a display screen with an animated graphical user interface showing our new design.

FIG. 5 is a fifth image of a sequence of a display screen with an animated graphical user interface showing our new design.

FIG. 6 is a sixth image of a sequence of a display screen with an animated graphical user interface showing our new design; and,

FIG. 7 is a seventh image of a sequence of a display screen with an animated graphical user interface showing our new design.

(Continued)

The portions of the design shown in broken lines or dashed lines are included for the purpose of illustrating environment and form no part of the claimed design.
